UNITED STATES PATENT OFFICE.

THEODORE M. FOOTE, DECEASED, LATE OF ALLSTON, MASSACHUSETTS, BY EMMA LURA FOOTE, EXECUTRIX, OF ALLSTON, MASSACHUSETTS, ASSIGNOR TO NATIONAL BINDING MACHINE COMPANY, OF NEW YORK, N. Y., A CORPORATION OF NEW YORK.

STRIP-SERVING APPARATUS.

1,284,289.

Specification of Letters Patent. Patented Nov. 12, 1918.

Application filed June 28, 1915. Serial No. 36,624.

To all whom it may concern:

Be it known that THEODORE M. FOOTE, deceased, late citizen of the United States, and resident of Allston, in the county of Suffolk and State of Massachusetts, invented an Improvement in Strip-Serving Apparatus, of which the following description, in connection with the accompanying drawings, is a specification, like characters on the drawings representing like parts.

This invention relates to strip serving apparatus.

In order that the principle thereof may be readily understood, he has disclosed a single embodiment thereof in the accompanying drawings, wherein—

Figure 1 is a front elevation of a strip serving apparatus embodying his invention;

Fig. 1^a is a detail in vertical section showing a portion of the strip severing means;

Fig. 2 is a rear elevation of the cam means for controlling the length of strip fed from the apparatus;

Fig. 3 is an edge view thereof;

Fig. 4 is a side elevation of the apparatus shown in Fig. 1;

Fig. 5 is a detail in side elevation of a portion of the apparatus shown in Fig. 4 and showing the parts differently positioned;

Fig. 6 is a plan view of the apparatus;

Fig. 7 is a horizontal section thereof, parts being shown in elevation; and

Fig. 8 is a vertical central section taken through the apparatus, parts thereof being shown in elevation;

This invention relates to apparatus for supplying strips of paper or the like employed for wrapping or binding packages or cartons, or for use as labels of any desired and preferably predetermined length, and an important object of the invention is to provide improved means for feeding an accurate and predetermined length of strip and for severing the same. Other important objects of the invention will be set forth hereinafter. The invention has particular reference to that type of apparatus employing a support for a coil or roll of paper strip previously gummed on one side and then dried and having means for moistening the gummed side of the strip as the latter is withdrawn from its coil or roll. It is apparent, however, that an ungummed strip of paper or the like might be used, in which

case the moistening device for the strip, suitably positioned with respect thereto, would contain an adhesive instead of water. Having reference to that single type or embodiment of his invention herein selected for illustration, the framing wherein preferably the strip serving apparatus is mounted is represented at 1, it being of any suitable material, preferably metallic, and herein shown as consisting of two plates of sheet metal suitably secured together by tie rods 2 or 65 in any other suitable manner. Obviously the apparatus may be mounted within a suitable casing instead of in the frame herein shown. In one wall of the frame on a suitable bolt or spindle 3, he mounts a suitable roll or drum 4 preferably of greater width than the roll or coil of paper 5 wound thereon, so that against an exposed portion of said roll he may position a suitable brake device or lever 6, herein represented as pivoted at 7 upon 70 the framing 1. The said brake lever is of arcuate form, so as to bear throughout an extended portion of its length upon the paper roll 4, the said brake having preferably upon its free end a loosely mounted roll 8 75 of wood or other suitable material. He has herein represented a spring 9 connected with the free end of said brake and with the frame as indicated at 10, so as to limit the movement thereof. The strip is passed 80 about said roll 8 as represented, and when drawn upon in the serving operation lifts said roll 8 against the tension of the spring 9, and thus lifts the brake off the strip roll and permits the serving of the strip. The 90 cessation of the strip feed permits the spring 9 to return the brake to normal position, thereby to prevent the strip roll from freely unwinding. The bolt or spindle 3, has an inner threaded end 11 adapted to receive 95 thereon a nut 12 adapted to engage the outer surface of a washer 13 and by means of which the strip roll is held in proper position on the drum 4. Preferably the nut 12 is composed of two portions pivoted together at 13' and provided with knurled members 14, 14, which may be pressed together in order to separate the threaded portion of the nut from the screw 11, and thus permit the withdrawal of the nut without 100 rotating it upon the thread 11. He contemplates the provision of means for feeding a 105 variable and predetermined length of strip,

and for that purpose he has, in the disclosed embodiment of the invention, provided two feed rolls indicated in the several figures, at 15 and 16, the lower feed roll 16 being a moistener roll, and for that purpose rotating in a tank or reservoir 17 which may contain water or an adhesive if desired. Preferably the said roll 16 is metallic, although he is not limited thereto, and preferably said roll has a slightly roughened surface, being preferably composed of brass.

The roll 15 is also preferably metallic, being herein represented as composed of brass, and is preferably fluted or corrugated as represented most clearly at 16' in Figs. 1 and 6. Preferably also each elevated portion of the corrugations is itself roughened as indicated at 17', 17' in said figures. By reason of the described roughening of said 20 rolls, he insures an accurate feeding of the strip. Preferably he provides springs 18 mounted upon the brackets at 19, and having heads or enlargements 20 adapted to bear upon the surface of the roll 15, thereby 25 to prevent operation thereof during non-service of the strip.

During non-service of the strip, the rolls 15, 16 are out of feeding relation with each other, and in order to feed the strip he relatively moves said rolls, thereby bringing them into feeding relation, and the length of strip served to the severing device is dependent upon the period of time during which said rolls 15, 16 are in feeding relation. By 35 varying said length of time, he varies the length of strip. While the mechanism for accomplishing this result may be widely varied within the scope and purpose of his invention, he preferably provides the following mechanism.

Upon the outer surface of one of the plates 1, he secures by means of a bolt 21 a gear 22 having upon the inner face thereof two cam disks 23, 24, the former having a cam surface 25, a portion of which is shown in full lines and a portion in dotted lines in Fig. 2. The portion of said surface 25 that is of greatest radial extent is indicated in full lines in said figure and at the point 26 it 50 slopes inwardly toward the portion of less radial extent shown in dotted lines. The disk 24 has a cam surface 27 shown wholly in full lines in said figure and consisting of two portions of different radial extent connected by a sloping portion 28, as clearly indicated in Fig. 2. In the position of the two disks 23, 24 shown in Fig. 2, the sloping portions 26, 28 thereof are separated by a short distance, and as hereinafter pointed out but 60 a very short length of strip can be served.

The said two disks 23, 24 are adapted to be relatively adjusted circumferentially of each other, and in the disclosed embodiment of the invention the disk 24 is adapted to be rotated upon the disk 23. For this purpose he

has represented the gear 22 and the disk 23 as having a circumferential slot 29 adapted to receive a short bolt 30 having a knurled head 31. By circumferentially adjusting the inner disk 24 by means of the circumferential slot 29 and then tightening the bolt 30, the distance between the sloping portions 26, 28 of the cam surfaces 25, 27 may be varied as desired, thereby correspondingly to vary the length of strip to be served. If desired 75 he may provide the gear 22 adjacent said groove 29 with a segmental scale 32, and suitably attached to or associated with the bolt and washer 30, 31, he may provide a pointer 33 co-operating with the scale 32.

Upon a suitable spindle or bolt 34, indicated most clearly in Fig. 4, he mounts a crank handle 35 and a small pinion 36 meshing with a pinion 37 fast to and co-axial with the moistener roller 16 and meshing directly 85 with the gear 22. Also meshing with the pinion 36 is an idler pinion 38 mounted upon the framing and meshing with a pinion 39 fast and co-axial with the upper feed roll 15. He pivots upon a pin or stud 40 extending through the frame a lever 41 having a roll 42 adapted to bear upon the cam surfaces 25, 26, 27, 28, the free end of said lever being connected by a spring 42' to the framing of the machine at 43.

Referring more particularly to Fig. 8, the pin or stud 40 between the two members of the frame has fast thereon a lever 44, the outer arm of which has connected thereto a coil spring 45 also connected to the framing at 46, thereby tending to move the opposite arm 47 of said lever downward. Upon said arm 47 of the lever, the upper feed roll 15 is loosely mounted.

From the foregoing construction, it will 105 be evident that so long as the roll 42 rides upon the cam surfaces 25, 27, which are of the greatest radial extent, the roll 15 will be held out of feeding relation with the lower or moistener feed roll 16. When, however, 110 the cam gear 22 is rotated through the action of the crank handle 35 and the interposed gearing, the inclined portion 28 will be brought into proximity with the roll 42 and the latter will therefore be permitted to 115 move radially inward, carrying with it the lever 41, and hence rocking the lever 44 upon the pin or stud 40, thereby bringing the feed roll 15 into feeding relation with the lower feed roll 16. Such feeding relation of the 120 feed rolls 15, 16 will continue until the rotation of the cam gear brings the inclined portion 26 of the cam surface 25 into engagement with the roll 42, whereupon the lever 41 will be rocked in the opposite direction, and the roll 15 separated from the roll 16 and the feeding of the strip, will thereupon 125 immediately cease. Preferably he provides a plate spring 48, shown most clearly in Fig. 8 as pivoted upon a transverse stud 49 and 130

adapted to bear upon the strip 50 at the point where it passes above the stud 40, and also preferably where it passes about a guide roll 51, thus preventing over-feeding of the strip. If desired and as indicated in Fig. 6, this plate spring may be of the entire width of the strip and may be slitted at intervals as represented at 52.

When the rolls 15, 16 are out of feeding relation, he preferably separates the strip 50 from contact with the moistener roll 16, thereby to prevent adherence of the strip to the roll. For this purpose, he so locates the stud 40 in the rear of the moistener and a guide 53 in advance of the moistener as to cause the strip to be elevated above the moistener when the roll 15 is separated from the moistener roll. While any suitable means may be provided to sever the strip, he preferably provides two cutter blades mounted transversely of the strip and having movement toward and also along each other, said severing blades being preferably operated by movement of the cam gear 22.

Referring more particularly to Figs. 1, 1^a, 4, 5 and 8, he provides slightly in advance of the feed rolls 15, 16, a cross piece 54 shown most clearly in Fig. 8, it being suitably slitted to permit the passage of the strip 50 between the lower guide 53 and an overlying guide 55. Loosely mounted for rocking movement adjacent opposite ends of the cross piece 54 are two disks 56, 57, herein represented as pivoted respectively at 58, 59. In advance of said disks 56, 57 he positions two cutter blades 60, 61. The blade 60 is provided at each end with arcuate slots 62, 63, and the blade 61 is provided at each end with corresponding slots 64, 65. These slots are adapted to receive screws 66, each passing through a small opening in one of said blades, and an arcuate slot in the other blade and being tapped into the proper disk 56, 57. The said arcuate slots 62, 63, 64, 65 being eccentric to the center of rotation of said disks, the construction is such that upon rocking movement of said disks, the blades are moved toward each other, and also lengthwise of each other, so as to sever the strip more readily and with a draw or wiping action.

He preferably provides a plate spring member 66' of substantially the same shape as the cutter blade 61, the purpose thereof being to maintain said blades 60, 61 in sufficiently close face to face relation to cut effectively. Said member is preferably provided with arcuate slots and openings registering with those of the blade 61, so as to be moved therewith.

Any suitable means may be provided to oscillate the disks 56, 57. For that purpose he preferably provides the disk 57 with an extension or pin 67, to which is pivotally connected a link 68, itself pivotally connected

to a vertical rod 69, the lower end 70 of which is pivotally connected to the arm 71 of a lever pivoted at 72 upon the framing of the machine and having an arm 73 adapted to be positioned in the path of a pin or stud 74 upon the surface of the cam gear 22. The construction is such that after the feeding of the strip has ceased, further rotation of the cam gear 22 brings the stud 74 into engagement with the lever arm 73 and moving 75 the same as indicated in Fig. 5, depresses the rod 69 and operates the severing blades to sever the predetermined length of strip. Said strip is thus delivered in a severed, moistened, unattached condition for manual application by the operator to the package or carton, or for such other purpose as may be desired.

He provides any suitable resetting means for the severing blades. For this purpose he has herein represented a lever mounted upon a stud 75 upon the frame and having arms 76, 77, the latter of which is adapted to engage a short arm 78 upon the lever 71, 72, 73, thereby to reset said lever 71, 72 and 73.

From the foregoing description, it will be evident that a strip of any length between certain extremes may be served, moistened and severed. The construction is such that the cam gear 22 makes one rotation for each complete operation of the mechanism, but the gearing herein represented is such that several complete rotations of the crank 35 are required to feed and sever a strip, the number of turns of course depending upon the length of strip. It is possible so to set the mechanism that a short strip measuring but a fraction of an inch may be served, or a much longer strip measuring two feet in length may be served. By suitably proportioning the parts and by changing the gearing, longer strips may obviously be served within the scope and purpose of his invention.

Having thus described one illustrative embodiment of his invention, he desires it to be understood that although specific terms are employed, they are used in a generic and descriptive sense and not for purposes of limitation, the scope of the invention being set forth in the following claims.

Claims:

1. In a strip serving apparatus adapted to feed a predetermined length of strip from a support having thereon a continuous strip, means to support a continuous strip of indefinite length, and means to feed therefrom a strip of predetermined length comprising feeding means for the forward end of the continuous strip, means to impart feeding movement to said feeding means, and means having movement with the said feeding movement-imparting means, thereby to bring the feeding means and the forward end of

- the strip into feeding relation for a predetermined period.
2. In a strip serving apparatus adapted to feed a predetermined length of strip from a support having thereon a continuous strip, means to support a continuous strip of indefinite length, feed rolls for the forward part of said indefinite length of strip, means to impart feeding movement to said feed rolls, and means having movement with the feeding movement of said rolls to bring said rolls and strip into feeding relation for a predetermined period.
3. A strip serving apparatus comprising in combination, a strip support, feed rolls for the strip, and means having a variable cam surface for determining the co-action of said feed rolls.
4. A strip serving apparatus comprising in combination, a strip support, co-acting feeding means, and means having a variable length cam surface for determining the action of the feeding means.
5. In a strip serving apparatus adapted to feed a predetermined length of strip from a support having thereon a continuous strip, means to support a continuous strip of indefinite length, feeding means for the forward portion of said continuous strip, means to impart feeding movement to said feeding means, means having movement with said feeding means to bring said feeding means and the forward end of the strip into feeding relation, and means to sever the free end of the strip.
6. In a strip serving apparatus adapted to feed a predetermined length of strip from a support having thereon a continuous strip, means to support a continuous strip of indefinite length, feeding rolls for the forward portion of said strip, means to rotate said feed rolls, means having traveling movement with said feed rolls to bring the feed rolls and the strip into feeding relation, and means to sever a predetermined length of strip from the forward end of said continuous strip.
7. A strip serving apparatus comprising in combination, a strip support, feeding rolls for the strip relatively movable out of feeding relation at the end of the feeding operation, thereby governing the length of strip fed, and means including variable length cam means for controlling said relative movement.
8. In a strip serving apparatus adapted to feed a predetermined length of strip from a support having thereon a continuous strip, means to support a continuous strip of indefinite length, feeding rolls for the strip relatively movable out of feeding relation at the end of the feeding operation, thereby governing the length of strip fed, means including cam means governing said feeding movement, and continuing the relative movement of said feeding rolls while out of feeding relation, and means for severing a predetermined length of strip from the forward end of said continuous strip.
9. A strip serving apparatus comprising in combination, a strip support, feeding rolls for the strip relatively movable into and out of feeding relation, and means including a gear having an adjustable cam for governing said relative movement.
10. A strip serving apparatus comprising in combination, a strip support, feeding rolls for the strip relatively movable out of feeding relation at the end of the feeding operation, thereby governing the length of strip fed, means including cam means governing said relative movement, and severing means operatively connected with said cam to sever the strip.
11. A strip serving apparatus comprising in combination, a strip support, feeding rolls for the strip relatively movable into and out of feeding relation, means including variable length cam means for controlling said relative movement, and severing means operatively connected with said cam to sever the strip.
12. A strip serving apparatus comprising in combination, a strip support, feeding rolls for the strip relatively movable out of feeding relation at the end of the feeding operation, thereby governing the length of strip fed, a rotatable cam member governing said relative movement, means to rotate said cam, and severing means controlled by said cam rotating means to sever the strip.
13. A strip serving apparatus comprising in combination, a strip support, feeding rolls for the strip relatively movable into and out of feeding relation, including a gear having an adjustable cam for governing said relative movement, and severing means controlled by said gear to sever the strip.
14. In a strip serving apparatus adapted to feed a predetermined length of strip from a support having thereon a continuous strip, means to support a continuous strip of indefinite length, feeding rolls for the forward end of said strip, said feeding rolls being relatively movable at the end of the feeding operation, thereby governing the length of strip fed, means including a rotatable cam member governing said relative movement, but permitting continued rotation of said feeding rolls while out of feeding relation, and means for automatically severing the forward end of the strip at a predetermined length from the free edge thereof.
15. A strip serving apparatus comprising in combination, a strip support, separable feeding rolls for the strip, one of said rolls being a moistener roll, means to impart a

feeding movement to said feeding rolls, and an element moved by the means for imparting movement to said feeding rolls relatively to separate said feeding rolls and the strip.

5 16. A strip serving apparatus comprising in combination, a strip support, separable feeding rolls for the strip, one of which is a moistener roll, means to rotate said feeding rolls and cam means operatively connected 10 with said feeding roll rotating means for governing the feeding relation of said rolls and to move them out of feeding relation at the end of the feeding movement.

15 17. A strip serving apparatus comprising in combination, a strip support, separable feeding rolls for the strip, one of which is a moistener roll, and means including a variable length cam for governing the action of said feeding rolls.

20 18. In a strip serving apparatus adapted to feed a predetermined length of strip from a support having thereon a continuous strip, means to support a continuous strip of indefinite length, feeding rolls for the strip 25 relatively movable out of feeding relation at the end of the feeding operation, thereby governing the length of strip fed and including means for rendering the strip adhesive, and means in advance of the feeding

30 rolls for severing the strip at a predetermined distance from the free edge thereof so as to provide an adhesive strip of predetermined length in flat condition for manual application.

35 19. A strip serving apparatus comprising in combination, a strip support, separable feeding means for the strip, means to impart feeding movement to said feeding means, and a variable length element moved by the 40 feeding movement of said feeding means, and governing the feeding relation of said feeding means.

45 20. A strip serving apparatus comprising in combination, a strip support, separable feeding rolls for the strip, means to rotate said rolls, one of which is a moistener roll, cam means movable with said feed roll rotating means for governing the feeding relation of said rolls, and to move them out of 50 feeding relation at the end of the feeding movement without necessary interruption of rotative movement of said feeding rolls, and means to sever the strip fed by said rolls.

55 21. A strip serving apparatus comprising in combination, a strip support, separable feeding rolls for the strip, one of which is a moistener roll, means including a variable length cam for governing the action of said feeding rolls, and means to sever the strip 60 fed by said rolls.

65 22. A strip serving apparatus comprising in combination, a strip support, separable feeding rolls for the strip, one of which is a moistener roll, a gear provided with means 70 governing the feeding relation of said rolls

and to move them out of feeding relation at the end of the feeding movement without necessary interruption of rotative movement of said feeding rolls, and means to sever the strip fed by said rolls.

70 23. A strip serving apparatus comprising in combination, a strip support, separable feeding rolls for the strip, one of which is a moistener roll, a gear provided with a variable length means for varying the feeding 75 relation of said rolls and to move them out of feeding relation at the end of the feeding movement, and means to sever the strip fed by said rolls.

75 24. In a strip serving apparatus adapted to feed a predetermined length of strip from a support having thereon a continuous strip, means to support a continuous strip of indefinite length, feeding rolls for the strip relatively movable out of feeding relation 80 at the end of the feeding operation, thereby governing the length of strip fed, said feeding rolls including means for rendering the strip adhesive, a severing blade in advance of the feeding rolls, means to operate the 85 same to sever the strip at a predetermined distance from the free end of the strip, and means to separate the then free end of the strip and the feeding rolls.

85 25. A strip serving apparatus comprising in combination, a strip support, a pair of feed rolls, one of which is mounted for bodily movement toward and away from the other, a variable length rotatable member, and a lever controlled by said member for 100 bodily moving said roll out of action at the end of the feeding movement.

90 26. A strip serving apparatus comprising in combination, a strip support, a pair of feed rolls, a gear, a lever controlled by said 105 gear, and means operated thereby bodily to move one of said rolls out of action at the end of the feeding movement but maintaining said feed rolls in driving relation to said gear.

95 27. In a strip serving apparatus adapted to feed a predetermined length of strip from a support having thereon a continuous strip, means to support a continuous strip of indefinite length, separable feeding rolls for 110 the strip, one of said rolls being a moistener roll, variable feeding means for controlling the feeding relation of said rolls and to move them out of feeding relation at the end of the feeding movement, and means to sever 115 the strip at a predetermined distance from the free edge thereof.

120 28. A strip serving apparatus comprising in combination, a strip support, a pair of feed rolls, a gear having a variable length 125 cam, a lever engaging said cam, and means operated by said lever for separating said feed rolls at the end of the feeding movement.

125 29. In a strip serving apparatus adapted 130

to feed a predetermined length of strip from a support having thereon a continuous strip, means to support a continuous strip of indefinite length, separable feeding rolls for the strip, one of said rolls being a moistener roll, a gear having means governing the feeding relation of said rolls and to move them out of feeding relation with each other at the end of the feeding movement while permitting their continued rotation out of feeding relation with each other, and means to sever the free end of the continuous strip at a predetermined distance from the free edge thereof, thereby providing a strip of predetermined length.

30. A strip serving apparatus comprising in combination, a strip support, a pair of feed rolls, a gear, a lever controlled by said gear, means operated thereby bodily to move one of said rolls at the end of the feeding movement but permitting continued movement of said roll, and strip severing means operated by said gear.

31. A strip serving apparatus comprising in combination, a strip support, a pair of feed rolls, a gear having a variable length cam, a member engaging said cam, means controlled by said member for separating said feeding rolls at the end of the feeding movement, and strip severing means operated by said gear.

32. A strip serving apparatus comprising in combination, a strip support, a pair of feed rolls, a gear having a cam, a lever engaging said cam, means operated by said lever for separating said feed rolls at the end of the feeding movement but permitting uninterrupted driving movement of said feed rolls, and strip severing means operated by said gear.

33. A strip serving apparatus comprising in combination, a strip support, a pair of feed rolls, a gear having a variable length cam, a lever adapted to be moved by said cam, a second lever adapted to be moved by the first and to separate said feed rolls at the end of the feeding movement and strip severing means operated by said gear.

34. A strip serving apparatus comprising in combination, a strip support, a pair of feed rolls, one of which is a moistener roll, means to rotate said rolls, means movable with said roll rotating means to move said rolls out of feeding relation at the end of the feeding movement but permitting uninterrupted driving movement of said feed rolls, and means to separate the strip and moistener roll upon separation of said rolls.

35. A strip serving apparatus comprising in combination, a strip support, a pair of feed rolls, one of which is a moistener roll, means to rotate said rolls, means having movement of rotation with said feed rolls to move said rolls out of feeding relation at the

end of the feeding movement but permitting uninterrupted driving movement of said feed rolls, strip severing means, and means to separate the strip and the moistener roll upon strip severance and the separation of said rolls.

36. A strip serving apparatus comprising a strip support, strip feeding rolls, strip moistening means, strip severing means, and variable length means movable with the feeding movement of said feeding rolls for determining the feeding relation of said rolls and for operating said severing means.

37. A strip serving apparatus comprising in combination, a strip support, relatively movable strip feeding rolls, strip severing means, and means movable with the feeding movement of said feeding rolls for separating the feeding rolls at the end of the feeding movement without necessarily stopping the driving movement of said feed rolls, for operating said severing means and for resetting said severing means.

38. A strip serving apparatus comprising in combination, a strip support, a pair of relatively movable strip feeding rolls, one of which is a moistener roll, variable means normally movable in the feeding action of the apparatus for separating said rolls to determine the feeding movement, strip-severing means, and means for resetting said severing means.

39. A strip serving apparatus comprising in combination, a strip support, opposed feeding members for the strip, and a cam having relatively adjustable members to govern the feeding relation of said opposed feeding members.

40. A strip serving apparatus comprising in combination, a strip support, a pair of opposed feed rolls having relative movement into and out of feeding relation, and a cam having relatively adjustable members to govern the feeding relation of said rolls.

41. A strip serving apparatus comprising in combination, a strip support, opposed strip feeding members relatively movable toward and from each other, one of said members being a moistener, means having movement during the feeding movement of said feeding members thereby to move said members out of feeding relation at the end of the feeding movement, but permitting continued driving movement of said feeding member, and means for separating the strip from the moistener.

42. A strip serving apparatus comprising in combination, a strip support, opposed strip feeding rolls relatively movable toward and from each other, one of said rolls being a moistener, means to rotate said rollers, variable length means relatively to move said rollers from each other at the end of the feeding movement, said means being

operatively connected to said means for operating the feed rolls, and means for separating the strip from the moistener roll.

43. A strip serving apparatus comprising in combination, a strip support, means to feed the strip therefrom, and a brake for the strip support controlled by draft upon the strip.

44. A strip serving apparatus comprising in combination, a strip roll support, a brake adapted to contact with said support, and means controlled by draft upon the strip to withdraw the brake from said strip support.

45. A strip serving apparatus comprising in combination, a strip roll support, feeding means for the strip, a brake lever for said support, and means controlled by draft upon strip to withdraw the brake from said strip support.

46. A strip serving apparatus comprising in combination, a strip support, opposed feeding members for the strip, strip severing means, resetting means for the severing means, and a gear controlling the feeding action of the opposed feeding members and effecting the continued driving movement of said opposed feeding members, and the severing action and the resetting of said severing means.

47. A strip serving apparatus comprising in combination, a strip support, feeding members therefor, and a cam controlling the action of said feeding members, said cam having a plurality of cam members and an annular slot for effecting adjustment thereof.

48. A strip serving apparatus comprising in combination, means including two separable rolls to moisten and feed a predetermined length of strip, means to drive said moistening and feeding means, means operatively connected to said driving means to terminate the feeding movement of said feeding means, but permitting the continued driving movement of said feeding means, means to sever the strip in advance of the moistener, and means to separate the free end of the strip from the moistener.

49. A strip serving apparatus comprising in combination, a strip support, relatively separable feed rolls, driving means therefor, a rotatable element operatively connected thereto to bring them into feeding relation to feed the strip, and means acting after separation of the rolls to sever the strip.

50. A strip serving apparatus comprising in combination, a strip support, relatively separable feed rolls, means relatively to move them into feeding relation to feed the strip, and thereafter to separate them, said latter means including a rotatable cam, and means acting after said feed roll separation to sever the strip.

51. A strip serving apparatus comprising in combination, a strip support, relatively

separable feed rolls, means to bring them into feeding relation to feed the strip, means to vary the period of strip feeding relation of said rolls, and means acting after separation of the rolls to sever the strip.

52. A strip serving apparatus comprising in combination, a strip support, relatively separable feed rolls, means relatively to move them into feeding relation to feed the strip, means to vary the period of strip feeding relation of said rolls, and thereafter to separate them, and means acting after said feed roll separation to sever the strip.

53. In a strip serving apparatus adapted to feed a predetermined length of strip from a support having thereon a continuous strip, means to support a continuous strip of indefinite length, a pair of feed rolls in peripheral feeding contact with each other, primary driving means for one of said rolls, a rotatable member, a lever controlled by said member to move one of said rolls out of feeding contact with the other at the end of the feeding movement but permitting continued rotative movement for the other of said rolls by said primary driving means, means for effecting the return of said roll to feeding contact, and coöperating means to sever the said strip.

54. In a strip serving apparatus adapted to feed a predetermined length of strip from a support having thereon a continuous strip, means to support a continuous strip of indefinite length, a pair of feed rolls, a gear having a cam, a member engaging said cam, means controlled by said member for separating said feed rolls at the end of the feeding movement without necessary interruption of the driving movement of said feed rolls, and coöperating means to sever the strip at a predetermined distance from the forward rear end thereof, thereby to provide a severed strip of predetermined length.

55. In a strip serving apparatus adapted to feed a predetermined length of strip from a support having thereon a continuous strip, means to support a continuous strip of indefinite length, a pair of feed rolls, a gear having a cam, a lever adapted to be moved by said cam, a second lever adapted to be moved by the first and to separate said feed rolls at the end of the feeding movement, but permitting continued driving movement of said feed rolls and coöperating means to sever the free end of the strip at a predetermined distance from the forward rear end thereof, thereby to provide a severed strip of predetermined length.

56. In a strip serving apparatus adapted to feed a predetermined length of strip from a support having thereon a continuous strip, means to support a continuous strip of indefinite length, a pair of feed rolls, a gear, a lever controlled by said gear, means operated

thereby bodily to move one of said rolls out of action at the end of the feeding movement without necessary interruption of the driving movement of said feed rolls, and operating means to sever the free end of the strip.

5 57. In a strip serving apparatus adapted to feed a predetermined length of strip from a support having thereon a continuous strip, means to support a continuous strip of indefinite length, a pair of feed rolls, a gear, a lever controlled by said gear, means operated thereby bodily to move one of said rolls out of action at the end of the feeding movement without necessary interruption of the driving movement of said feed rolls, coöperating means in advance of the feed rolls to sever the free end of the strip, and means to separate the then free end of the continuous strip and the feed rolls.

10 58. In a strip serving apparatus adapted to feed a predetermined length of strip from a support having thereon a continuous strip, means to support a continuous strip of indefinite length, a separable plural feeding

means for the strip, means having a primary driving element to impart feeding movement to said feeding means, an element moved by the feeding movement of said primary driving element and governing the feeding relation of said feeding means and permitting the constant movement of said primary element, and a member of said plural member feeding means, means for effecting strip feeding movement of said separable plural member feeding means and coöoperating means to sever the fed strip at a predetermined distance from the forward free edge thereof, whereby a severed strip of predetermined length is provided.

15 In testimony whereof, I have signed my name to this specification in the presence of two subscribing witnesses.

EMMA LURA FOOTE,
Ex-citrix of Theodore M. Foote, deceased.
